UNITED STATES PATENT OFFICE

165,674

LADY'S STOCKING

Victor J. Voss, New Britain, Pa.

Application May 3, 1951, Serial No. 15,047

Term of patent 14 years

(Cl. D47—7)

To all whom it may concern:

Be it known that I, Victor J. Voss, a citizen of the United States, residing at New Britain, county of Bucks, and Commonwealth of Pennsylvania, have invented a new, original, and ornamental Design for a Lady's Stocking, of which the following is a specification, reference being had to the accompanying drawing, wherein:

Figure 1 is a view in rear elevation of a portion of a stocking embodying the design of this invention; and

Fig. 2 is a perspective view of the complete stocking taken from an angle different from that from which Fig. 1 is taken.

I claim:

The ornamental design for a lady's stocking, as shown.

VICTOR J. VOSS.
